B. B. MYERS.
FOLDABLE SUNSHADE FRAME.
APPLICATION FILED NOV. 6, 1919.

1,407,040.

Patented Feb. 21, 1922.

UNITED STATES PATENT OFFICE.

BERTHA B. MYERS, OF LOS ANGELES, CALIFORNIA.

FOLDABLE SUNSHADE FRAME.

1,407,040.

specification of Letters Patent. Patented Feb. 21, 1922.

Application filed November 6, 1919. Serial No. 336,114.

To all whom it may concern:

Be it known that I, BERTHA B. MYERS, a citizen of the United States, residing at Los Angeles, in the county of Los Angeles and State of California, have invented new and useful Improvements in Foldable Sunshade Frames, of which the following is a specification.

This invention relates to a foldable frame and particularly pertains to a support for a sunshade of the type set forth in United States Letters Patent No. 1,297,225 issued to me March 11, 1919.

It is the object of this invention to provide a frame for supporting a flexible covering of fabric or the like whereby a substantially rectangular canopy may be formed, which is especially applicable for use as a sunshade and shelter for bathers.

Another object is to provide a frame of the above character which is foldable so that it may be collapsed into a compact space and rendered convenient for storage and transportation.

A further object is to provide a foldable frame which is so designed that it may be made of few light parts so assembled as to afford a strong and substantial structure and adapted to be securely locked in its open position against accidental collapse.

Other objects will appear hereinafter.

The invention is illustrated in the accompanying drawings, in which:

Figure 1 is a perspective view of the frame as seen in its open position and adapted to receive the canopy as indicated in dotted lines.

Figure 2 is a perspective view of the frame showing it in a partly folded position.

Figure 3 is a view in end elevation of the frame in its folded position.

In carrying out my invention, I form a frame embodying a horizontal top bar 4 fitted at its ends with foldable side stands 5 and 6 pivoted adjacent to the ends of the top bar. In forming the connection between the top bar and the standards, the ends of the top bar are turned downwardly, as indicated at 7, to which the standards are secured by pivot pins 8. A flange 9 is formed on each portion 7 to form an abutment for limiting the outward pivotal movement of the standard; this flange extending alongside the outer edge of the standard axially of the pivotal mounting thereof.

Each standard is formed of a plurality of sections 10 and 11 which are connected together by a pivot pin 12, so that the sections may be folded together and swung on the pivot 8 to extend substantially parallel with the bar 4.

As a means for substantially locking the sections 10 and 11 in alignment with each other, the lower section 11 has an elongated and slightly tapered end portion 13 adapted to overlap the upper section 10 and to receive a sleeve 14 slidable on the section 10 and adapted to encircle both the section 10 and the extended portion 13 of section 11 to retain the sections in alignment and securely hold them against pivotal movement relative to each other in their open position.

The lower ends of the standards are preferably pointed to permit their being readily forced into the ground. The elements just described constitute the main portion of the foldable frame and when unfolded and placed in position, constitute a single top bar supported at each end on a single standard and forming a substantially rectangular structure.

An important feature of this invention resides in means whereby this single support may be adapted to carry and form a frame for a box like canopy. This means is here shown as residing in a pair of foldable end arms 15 and 16 pivotally mounted relative to the top bar 4 adjacent to the down turned end portions 7; these arms being connected by pivots 17 to a transverse supporting plate 18 fastened to the top bar so as to adapt the arms to swing in a virtually horizontal plane, and the plate 18 having upturned end flanges 19 arranged to project in the path of travel of the outward movement of the arms 15 and 16, and to position the latter in alignment with each other, and extending at right angles to the top bar.

A spring plate 20 secured to the upper face of the top bar and having a limited yieldable upward movement relative thereto has down turned side flanges 21 adapted to project alongside the arms 15 and 16 opposite to flanges 19, so as to cooperate with the latter in holding the arms against movement in their open position; the spring plate being adapted to be bent upwardly to permit the arms 15 and 16 to be swung inwardly into their folded position alongside of the top bar 4 where their outer edges will be en-

gaged by the down turned flanges 21, whereby the arms will be securely held in their folded position, as shown in Figure 2.

The outer ends of the arms 15 and 16 are fitted with buttons 22 or other suitable fastenings for engagement with eyelets 23 or the like indicated in dotted lines of a box like canopy 24. This canopy is formed with a rectangular top wall, indicated at 25, 10 adapted to be supported on the frame formed by the top bar 4 and the arms 15 and 16, and has a back wall portion, indicated at 26, substantially conforming in size and outline to the space encircled by the rectangular frame. The canopy is also formed with side portions 27 adapted to depend from the arms 15 and 16 and to extend downwardly into engagement with foldable cross arms 28 pivoted at 29 near the lower 20 ends of the standard sections 11, which cross arms have buttons 30 or other suitable fastenings for engagement with the lower ends of the canopy side portions.

In folding the frame, the cross arms 28 are turned to extend parallel with the sections 11, whereupon the sections 11, on loosening the sleeve 14, are folded to extend alongside the sections 10, which are then swung inwardly on their pivots 18 to extend 30 substantially parallel with the top bar 4. The arms 15 and 16 are then swung inwardly and engaged by the spring plate 20, as before described, thus folding the frame into a compact space forming a small package convenient for transportation.

I claim:

1. A foldable frame comprising a single top bar, a standard secured to each end of said bar for supporting same, and a pair of arms pivoted at each end of said bar so as to be adapted to swing in a virtually horizontal plane and to extend outwardly on opposite sides of the bar.

2. A foldable frame comprising a single top bar, a standard secured to each end of said bar for supporting same, a pair of arms pivoted at each end of said bar so as to be adapted to swing in a virtually horizontal plane and to extend outwardly on opposite sides of the bar, and means for detachably locking said arms in their extended position.

3. A foldable frame comprising a single top bar, a standard secured to each end of said bar for supporting same, a pair of arms pivoted at each end of said bar adapted to extend outwardly on opposite sides thereof, and a spring plate at each end of said bar adapted to engage said arms to lock same in their extended position.

4. A foldable frame comprising a single top bar, a standard secured to each end of said bar for supporting same, a pair of arms pivoted at each end of said bar adapted to extend outwardly on opposite sides thereof, and a spring plate at each end of said bar

adapted to engage said arms to lock same in their extended position, said spring plate also adapted to hold said arms in a folded position.

5. A foldable frame comprising a single top bar, a standard pivotally secured to each end of said bar for supporting same, each of said standards comprising foldable members adapted to be secured in alinement with each other and to be folded alongside each other, and a pair of arms pivoted at each end of said bar as to be adapted to swing in a virtually horizontal plane and to extend outwardly on opposite sides of the bar.

6. A foldable frame comprising a single top bar, a standard secured to each end of said bar for supporting same, a pair of arms pivoted at each end of said bar so as to be adapted to swing in a virtually horizontal plane and to extend outwardly on opposite sides of the bar, and a cross arm attached to the lower portion of said standard.

7. A canopy comprising a cover formed with a rectangular top wall, a dependent back wall and side walls connected to said back wall and to the ends of the top wall, a top bar extending longitudinally of said top wall centrally thereof, a standard secured to each end of said top bar for supporting same, and a pair of arms pivoted to each end of said top bar so as to be adapted to swing in a virtually horizontal plane and to extend on opposite sides of the top bar at the intersection of the top and side walls of said cover.

8. A canopy comprising a cover formed with a rectangular top wall, a dependent back wall and side walls connected to said back wall and to the ends of the top wall, a top bar extending longitudinally of said top wall centrally thereof, a standard secured to each end of said top bar for supporting same, a pair of arms pivoted to each end of said top bar so as to be adapted to swing in a virtually horizontal plane and to extend on opposite sides of the top bar at the intersection of the top and side walls of said cover, and means for detachably connecting the outer ends of said arms to the cover.

9. A canopy comprising a cover formed with a rectangular top wall, a dependent back wall and side walls connected to said back wall and to the ends of the top wall, a top bar extending longitudinally of said top wall centrally thereof, a standard secured to each end of said top bar for supporting same, a pair of arms pivoted to each end of said top bar so as to be adapted to swing in a virtually horizontal plane and to extend on opposite sides of the top bar at the intersection of the top and side walls of said cover, means for detachably connecting the outer ends of said arms to the cover, and a cross arm attached to the lower por-

tion of each of said standards adapted to be attached at its ends to the cover side portions.

10. In a foldable sunshade, a cover comprising a top wall, a back wall and side walls, a top bar adapted to extend lengthwise of the top wall centrally thereof, a standard pivoted to each end of said top bar for supporting same, a pair of arms pivoted to each end of said top bar so as to be adapted to swing in a virtually horizontal plane and to extend on opposite sides of said top bar at the intersection of the cover top and side walls, means for locking said arms in their extended position, means for connecting the cover to each of said arms, a cross arm pivoted on the lower portion of each standard, and means for attaching the outer portion of each of said cross arms to the cover side walls.
11. In a foldable sunshade, a cover com-

prising a top wall, a back wall and side walls, a top bar adapted to extend lengthwise of the top wall centrally thereof, a standard pivoted to each end of said top bar 21 for supporting same, a pair of arms pivoted to each end of said top bar so as to be adapted to swing in a virtually horizontal plane and to extend on opposite sides of said top bar at the intersection of the cover top and 30 side walls, means for locking said arms in their extended position, means for connecting the cover to each of said arms, a cross arm pivoted on the lower portion of each standard, and means for attaching the outer 35 portion of each of said cross arms to the cover side walls, each of said standards comprising a plurality of pivotally connected sections adapted to be secured in longitudinal alinement with each other.

BERTHA B. MYERS.
